CLAIM

The ornamental design for a handset, as shown and described.

DESCRIPTION

FIG. 1 is a perspective front view of a handset showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the environment of the handset in FIGS. 1-7 is for illustrative purposes only and forms no part of the claimed design. The unshaded regions within the boundaries formed by the broken lines are not a part of the claimed design.
